UNITED STATES PATENT OFFICE.

HAROLD N. SHAW, OF MILWAUKEE, WISCONSIN.

AUTOMATIC CIRCUIT MAKER AND BREAKER.

Application filed May 8, 1922. Serial No. 559,821.

To all whom it may concern:

Be it known that I, HAROLD N. SHAW, a citizen of the United States, and resident of Milwaukee, in the county of Milwaukee and

5 State of Wisconsin, have invented new and useful Improvements in Automatic Circuit Makers and Breakers, of which the following is a description, reference being had to the accompanying drawings, which are a

10 part of this specification.

This invention relates to automatic circuit makers and breakers and has for its object to provide an automatic electro-magnetic switch which may be effectively employed 15 for controlling electrical circuits of various kinds, such for example as the circuit of an electric heating device, whereby the temperature thereof may be maintained substantially constant.

20 A further object of the invention is to provide a device of the class described which may be operated by the changes or variations in the current taken by the heating element as its temperature varies.

25 A still further object of the invention is to provide a device of the character described which is simple in construction, comparatively inexpensive to manufacture, and more efficient in use than those which 30 have been heretofore proposed, and which is entirely independent of the heating device or other apparatus with which it may be employed.

With these and other objects in view, the 35 invention consists in the novel details of construction, and combinations of parts more fully hereinafter disclosed and particularly pointed out in the claims.

In the accompanying drawings in which 40 like numerals designate like parts in all the views;

Figure 1 is a top plan view of an electro-magnetic switch made in accordance with the present invention, a portion of the cover 45 plate and certain other parts being broken away for the sake of clearness;

Fig. 2 is a transverse sectional view taken approximately on the plane indicated by the line 2-2 of Fig. 1, looking in the direction of the arrows;

Fig. 3 is a fragmentary cross sectional view through one pair of contact members, taken approximately on the plane indicated by the line 3-3 of Fig. 1;

Fig. 4 is a wiring diagram illustrating 55 the connections between the switch shown in Figs. 1 and 2 and a plurality of resistance heating coils such as are commonly employed in an electrical heating apparatus; and

Fig. 5 is a diagrammatic plan view of a slightly modified form of the invention.

Referring more especially to Figs. 1 and 2 the numeral 10 indicates a frame which is preferably composed of a plurality of laminations or metallic sheets 11, which preferably takes the form of a hollow square as seen in plan. The inner sides of the said square are provided with the pairs of oppositely disposed projections 12 and 13, 65 constituting pole pieces which are adapted to receive the coils or windings 14 and 15 respectively, as will be clear from Fig. 1. The said laminations are provided on their tops and bottoms with the heavier strengthening members 17 all of the said laminations as well as the said members 17 are closely compacted and securely welded to the tubular supporting members 18.

One pair of the said members 18 has secured to its top and bottom ends respectively, the transversely extending bearing members 19 and 20, which are secured to the said supporting members 18 by means of the vertically extending bolts 21 passing through the bores of the said members 18, as will be clear from Fig. 2. The bearing members 19 and 20 are centrally drilled to provide bearings for the shaft 22, which shaft carries an armature 23 composed of a plurality of laminations built up and secured to the said shaft by welding, or in any other suitable manner, similar to the construction described in connection with the field member 10.

The said armature is of a diameter slightly less than the distance between the opposing field poles, 12 and 13, in order to provide a small air gap as is usual in this class of apparatus and the said armature is of a width sufficient to a little more than bridge the angular gap between two adjacent field poles.

The arcuate faces of the armature have secured to them by welding, or in any other 105 suitable manner, the stop members 24 of a width slightly less than the angular distance between two adjacent field poles, as

will be clear from Fig. 1. The said stop members 24 are thus adapted to oscillate between adjacent fields and to engage the side faces thereof, in order to limit the 5 movement of the armature, as will presently appear.

The shaft 22 has rigidly secured to it adjacent the transverse bearing member 19, an arm 25 of suitable insulating material, 10 The said arm 25 is provided with a pair of oppositely disposed metallic contact members 26 and 27, preferably set flush with the surfaces of the said arm in suitable recesses provided therein and retained in place by 15 means of the screws or other fastenings 28 and 29 respectively.

The said contact members 26 and 27 are adapted to move with the said arm 25 and shaft 22 to engage a pair of relatively stationary contact members 30 and 31, secured to and insulated from the bearing arm or member 19 by means of the clips 32 and 33 and the bolts or screws 34 and 35. The said contact members 30 and 31 preferably comprise a plurality of wires placed adjacent one another and soldered together, the ends of which are bent upwardly as at 36, see Fig. 3.

This construction provides an inexpensive 30 yet efficient resilient contact member which has been found to answer all the requirements for this type of device. The bend 37 in the said contact members 31 is adapted to engage the top surface of the movable 35 contact carrying arm 25 and the contacts 26 and 27 carried thereby, as will be readily apparent.

In the particular form of the device herein illustrated, the coils 15 are preferably 40 formed in three separate and distinct parts indicated by the numerals 40, 41 and 42.

As above stated, the switch is especially 45 adapted for use in connection with electric heating elements for the purpose of automatically controlling their temperature. In Fig. 4 there is diagrammatically illustrated a heating element 50 comprising the four resistance coils 51, 52, 53, and 54. In order to control this said heating element by 50 means of the switch constituting the present invention the coils 14 of the said switch are connected in series with the resistance coil 51. The coils 40 are connected in series with the resistance element 52, the coils 41 are 55 likewise connected in series with the resistance element 53, and the coils 42 are connected with the resistance element 54.

One end of the coils 40 is connected to one end of the coils 41 by means of a wire 60 55, and one end of the resistance element 53 is connected to one end of the resistance element 54 by means of a wire 56.

The wire 57 leads from one end of the coils 14 to a resistance element or coil 58, 65 the other end of which is connected to the

main supply lead 59, as will be readily understood. A shunt circuit, 60, including a switch 61 may be provided for cutting out the resistance 58 under certain conditions or when desired. The other main lead wire 62 is connected to the other end of the resistance coil 51, as will be readily understood, and it is also connected by means of a wire 63 to one end of the resistance element 52.

The contact members 27 and 31 of the automatic switch above described are connected by means of wires 64 and 65, respectively, to the lead wire 62 and the wire 56, as will be clear from Fig. 4. In like manner the contact members 26 and 30 of the said switch are connected respectively by the wires 66 and 67 to the wires 59 and 55. One end of the coils 42 is connected by the wire 68 to the return lead 59 in order to complete its work.

The operation of the device is as follows:

Supposing the resistance element to be cold, the switches open and the power just turned on, the current will pass from line 62 to and through the resistance coil 51, coils 14 of the automatic switch, along wire 57, through resistance 58 to the return wire 59. The current will also pass from the said wire 62 by way of wire 63 through the resistance coil 52, coils 40 of the automatic switch, wire 55, to and through coils 41 of the said switch, thence through the resistance element or coil 53, along wire 56 to and through resistance coil 54, then through coils 42 of the switch and along wire 68 to the return wire or lead 59.

Under these conditions the coils 14 exert a much weaker magnetic influence than do the coils 40, 41, and 42 of the field elements 15, thereby causing the rotor or armature 23 to move in a clock-wise direction, as seen in Fig. 1. This movement of the said armature is, of course, transmitted through the shaft 22 to the contact carrying arm 25, thereby causing the contacts 26 and 27 to move under and engage with the stationary contacts 30 and 31.

Before the closing of these switches, it will be noted that the resistance coils 52, 53 and 54 and the coils 40, 41 and 42 of the automatic switch were all connected in series. However, when the switch contacts 26, 30, 27, and 31 are thus closed, the coupling of the above mentioned coils is changed from series to parallel, thereby changing the direction of the current flow through the resistance coil 53 and the coils 41 of the automatic switch.

The field coils 40, 41 and 42 of the switch are so wound and connected that when they are coupled and actuated in series, as above disclosed, their magnetic effect is cumulative; in other words with the current flowing through the coils, when connected in se-

ries, they all tend to produce one polarity on the upper field pole, and the opposite polarity on the opposite field pole.

However, when the coupling is changed from series to parallel, the direction of the current flowing through the coils 41 is reversed, thereby reversing the polarity thereof, and consequently weakening the magnetic strength of the field poles 13.

10 When the switches are opened and the various coils 52, 53, 54, 40, 41, and 42 are connected in series, a certain amount of current flows through all of the coils and a certain pull is exerted upon the rotor or 15 armature 23. Supposing, for example, that this current be one ampere, when the coils are connected in series, when the coupling is changed to parallel by the closing of the switch contacts 26 and 30, and 27 and 31, a 20 current of three amperes will flow through each section or nine amperes in all, and only one of the coils 40, 41, or 42 would be effective, inasmuch as the other two oppose and neutralize each other.

25 However, since three times the amount of current is flowing through the effective turns, the pull upon the rotor or armature 23 does not change and the said armature keeps moving until the stop members 24 engage with the pole pieces 13 and the contacts 26 and 30, and 27 and 31 are fully closed.

The heating element comprising the coils 51, 52, 53, and 54 will now heat up rapidly and when the desired maximum temperature is reached the coils 15 become weaker than the coils 14, thereby causing the rotor to move in a counter clockwise direction and opening the switch contacts 26 and 30, and 40 27 and 31. As the temperature of the heating element falls, the coils 15 again become stronger, with the result that the switch contacts are again closed, thus coupling the resistance elements in parallel instead of in 45 series with a consequent increase in the current consumed and the amount of heat given off.

It will thus be seen that this switch will automatically maintain a substantially constant temperature within certain limits, inasmuch as whenever the temperature rises to a desired maximum, the resistance coils will be connected in series, thus reducing the amount of heat generated, and whenever 55 the temperature falls to a predetermined minimum they will automatically be connected in parallel, thereby increasing the current consumed and the amount of heat given off.

60 The resistance coils 52, 53, and 54 of the heating device are preferably composed of a material having a suitable temperature coefficient of resistance, i. e. the resistance thereof changes with their temperature in 65 a certain determined amount. On the other

hand the resistance coil 51 is preferably composed of a material having a temperature coefficient of resistance of substantially zero. In this way the magnetic effect of the field coils 14 of the switch may be maintained substantially constant, while that of the field coils 15 may be made to vary, as above disclosed, depending upon the temperature of the said coils 52, 53, and 54. In one form of heating device, the said coils 52, 53, and 54 may be made of a nickel ribbon which has a certain predetermined temperature coefficient of resistance and which is suitable for a particular class of the work.

In Fig. 5 there is shown a slightly modified form of the automatic switch in which the rotor or armature stampings may be so shaped as to provide integral stop members adapted to engage the pole pieces of the field coils.

This construction is particularly adapted for use with an alternating current shunt coil control device and its operation is substantially the same as that above described in connection with the form shown in Figs. 1, 2, and 3, which form is more especially adapted for use with a direct current.

However, when the switch is used with an alternating current or transformer type of heating element, the coils 14 should be replaced by shunt coils and the pole faces shaped substantially as shown in Fig. 5, so as to have a variable gap.

It is necessary with this type of switch that the movable switch member be actuated relatively quickly one way or the other in order to prevent destructive arcing between the contacts. This is accomplished by the stop pieces 24 because as they leave the poles with which they have been in contact, their attraction falls off and this force is available for the acceleration of the rotor.

It is obvious that those skilled in the art may vary the details of construction, as well as the arrangement of parts without departing from the spirit of the invention, and therefore it is not wished to be limited to the above disclosure, except as may be required by the claims.

What is claimed is:

1. An automatic circuit controlling device comprising a plurality of contact members; and means responsive to variations in the resistance of an electric circuit, for controlling said contact members.

2. An automatic circuit controlling device comprising a plurality of contact members adapted to be included in an electric circuit; and means also included in said circuit and responsive to changes in the resistance thereof, for controlling said contact members.

3. An automatic temperature controlling device comprising a plurality of contact members adapted to be included in an elec-

tric circuit with a resistance heating element; and magnetic means also included in said circuit and responsive to variations in the resistance thereof, for controlling 5 said contact members.

4. In an automatic switch the combination of a relatively stationary field member; a movable armature member; contacts carried by said field member; additional 10 contacts carried by said armature member, for engagement with said field-carried contacts; and windings carried by said field member, responsive to changes in the resistance of an electric circuit, for controlling 15 the movements of said armature.

5. In an automatic switch the combination of a relatively stationary field member; a movable armature member; stops carried by said armature for limiting its 20 movement; contacts carried by said field member; additional contacts carried by said armature member, for engagement with said field-carried contacts; and windings carried by said field member, responsive to 25 changes in the resistance of an electric circuit, for controlling the movements of said armature.

6. An automatic switch for controlling the temperature of an electric heating element comprising a field frame having a plurality of pairs of oppositely disposed 30 pole members; a shaft rotatably mounted in said frame; an armature carried by said shaft; a plurality of pairs of contact members carried by said frame and armature, for making and breaking circuit; windings 35

upon one pair of said field pole members adapted to produce a substantially constant magneto motive force therein; additional windings upon another pair of said pole 40 members for producing a magneto motive force therein; and connections between said contact members and the said last mentioned windings, whereby the effective magneto motive force produced by the latter 45 will be the same with either series or parallel connections, but will vary with the temperature of the heating element.

7. In an automatic switch the combination of a relatively stationary field member; a movable armature member; stops carried by said armature for limiting its movement; contacts formed of a plurality of parts carried by said field member; additional contacts carried by said armature member, for engagement with said field-carried contacts; and windings carried by said field member, responsive to changes in the resistance of an electric circuit, for controlling 55 the movements of said armature.

8. An automatic switch having salient field poles and a rotor so shaped that as the latter moves the magnetic flux changes 60 at a constant rate in the case of series coils, and the magneto motive force changes at a constant rate in case of alternating current shunt coils.

In testimony whereof, I affix my signature.

HAROLD N. SHAW.
